C. F. STODDARD

NOTE SHEET

Original Filed July 7, 1908

Inventor
Charles F. Stoddard.

By his Attorney
George Vaneen, New York

UNITED STATES PATENT OFFICE.

CHARLES F. STODDARD, OF NEW YORK, N. Y., ASSIGNOR TO AMERICAN PIANO COMPANY, OF NEW YORK, N. Y., A CORPORATION OF NEW JERSEY.

NOTE SHEET.

Original application filed July 7, 1908, Serial No. 442,288. Patent No. 1,409,478, dated March 14, 1922.

Divided and this application filed March 13, 1922. Serial No. 543,148.

To all whom it may concern:

Be it known that I, CHARLES F. STODDARD, a citizen of the United States, and a resident of the city, county, and State of New York, have invented an Improvement in Note Sheets, of which the following is a specification.

The present invention relates to perforated note sheets for automatic musical instruments such as player pianos and the like and has for one of its objects the improvement in the relative location and arrangement of note sounding and expression controlling perforations in the sheet whereby, in cooperation with appropriate mechanism, the operation of an instrument, particularly as to the tone intensity, may be more advantageously controlled.

The present application is filed as a division of a copending application originally filed by me on July 7, 1908, Serial No. 442,288 and renewed on October 27, 1917, Serial No. 198,880, upon which said application a patent has been granted, No. 1,409,478 of March 14, 1922.

For purposes of illustration and description, the embodiment of the present invention shown and described in the above mentioned copending application has been selected and shown in the accompanying drawing.

In my above mentioned copending application there is shown and described a preferred embodiment of a certain invention in expression governing mechanisms for automatic musical instruments with which the illustrative note sheet of the drawings was primarily designed to cooperate. It will be apparent to one skilled in the art that a note sheet embodying the present invention may be designed to cooperate with expression mechanisms other than that just referred to. Therefore for the purposes of this application it is deemed unnecessary to explain an expression mechanism with which the note sheet of this application may cooperate. Reference may be had to the above mentioned copending application if necessary.

It is sufficient for the purposes of this application to show in the accompanying drawings a tracker T provided with the usual tracker vents for the sounding of notes and with additional tracker vents which may be connected with suitable expression

mechanism in order to control the intensity of playing. In the specific illustration six expression controlling vents are provided and identified by the letters A to F inclusive. In order to understand the present invention it may be assumed that vents A, C and E when opened separately operate to decrease playing intensities, each to a different extent and that the opening of vents B, D and F will negative the effect of opening vents A, C and E respectively. It may further be assumed that the respective effects obtained by the opening of any one of vents A, C or E may be superposed upon the effects obtained by the previous opening of any other of these three vents to produce the combined effect of the combination; the result being maintained until negated by the appropriate opening of the cancel vents B, D and F. For a further explanation reference may be had to the above mentioned patent.

It is assumed that the note sheet is adapted to move over the tracker bar in the direction of the arrow, that is, downwardly. The vertical dotted lines at the right of the sheet are for the purpose of making the alignment of perforations and tracker vents more apparent and the transverse dotted lines are for the purpose of showing more plainly the alignment of note sounding and expression controlling perforations.

Referring first to the group of note sounding perforations and expression controlling perforations at the upper part of the sheet, it will be seen that perforations A¹, C¹ and E¹ will, when registering with their respective vents in the tracker bar, operate to decrease playing intensities to the minimum for which the instrument may be adjusted. When the note perforation N¹ opens its corresponding vent in the tracker bar a note will be sounded with minimum intensity. As the note sheet progresses across the tracker bar, expression controlling perforation F¹ will open its corresponding vent, thus canceling the effect of perforation E¹ and raising playing intensities slightly so that when note perforation N² registers with the tracker bar its corresponding note will be sounded with increased intensity. As the note sheet progresses further the perforations E² and D¹ will open their corresponding vents and restore the effect pro-

duced by perforation E¹ while cancelling the effect produced by the perforation C¹. Inasmuch as the increase in playing intensity, due to the opening of vents E, C and A may be progressively greater in the order named, the result will be that upon the registration of note sounding perforation N³ with the tracker bar its note will be sounded with still greater intensity. Inasmuch as the perforation F² will register with its vent in the tracker bar before the next note sounding perforation N⁴ sounds a note, the effect of the previous perforation E² will be cancelled and playing intensity still further increased before N⁴ sounds its note.

In similar manner playing intensities may be gradually increased as the note sounding perforations N⁵, N⁶, N⁷, and N⁸ come into registration with the tracker, for example, prior to the sounding of a note by N⁵, perforation B¹ will have cancelled the effect of A¹, perforation C² will have restored the effect of perforation C¹ and perforation E³ will have restored the effect of E². Thereafter the effect of E¹ will be cancelled by the perforation F⁴ and playing intensities increased slightly before the sounding of a note by N⁶. Then the perforation D² will cancel the effect of perforation C² while the effect of perforation E⁴ will be restored by perforation E⁵ before the sounding of a note by perforation N⁷. In order to produce the maximum intensity it is then only necessary for perforation F⁴ to register with its vent in the tracker bar thereby canceling the effect of E⁴ and raising the playing intensity to the maximum.

The foregoing serves to illustrate a preferred arrangement of expression controlling perforations themselves but it will at once be apparent to those skilled in the art that other arrangements of expression controlling perforations may be used in carrying out the present invention; the foregoing being one of several possible plans or arrangements.

In the above illustration it has been assumed that each successive note is struck with increasing intensity. Obviously the relative arrangement of note sounding perforation and expression controlling perforations may be varied at will to sound notes successively with decreasing intensity or in any manner desired or appropriate to the musical composition being rendered.

In the rendition of a musical composition on an automatic instrument in such manner that the original playing of an artist will be faithfully reproduced, it is often desirable or necessary to accent a note or notes in a chord, that is, to sound with greater intensity one or more of a group of notes which are struck substantially simultaneously. It is to this problem that the present invention is particularly directed.

Referring to the illustrative group of note sounding and expression controlling perforations at the lower part of the drawing and assuming that that part of the sheet is about to pass over the tracker, it will be observed that the note corresponding to the perforation N⁹ will be sounded at an intensity somewhat less than the maximum by reason of the prior registration of perforation E⁶ with its corresponding tracker vent. The next group of notes sounded by the perforations N¹⁰, N¹¹, and N¹² will be sounded at a still lower intensity due to the registration of the perforation C⁶ with its corresponding vent in the tracker. Of the next two notes N¹³ and N¹⁴ which are indicated upon the score to be sounded substantially simultaneously it may be desired to accent the note controlled by perforation N¹³, as in the case of a theme note, for example. Therefore the advance end of this note sounding perforation may be moved slightly forward of its normal position and the expression controlling perforations A⁶ and B⁶, which operate to reduce playing intensities still further may be so located that the note sounded by perforation N¹³ will not be affected thereby, but the note sounded by perforation N¹⁴ will be, as to its intensity, affected by these expression perforations A⁶ and D⁶. Thus in order to emphasize the theme note N¹³ so that it shall be more prominent than the accompaniment, expression controlling perforations A⁶ and D⁶ may reduce the intensity of the note played by the accompaniment perforation N¹⁴, the theme perforation N¹³ being moved forward on the sheet so that it shall be beyond the effect of the intensity reducing perforations A⁶ and D⁶.

In the interval between the sounding of notes the perforations B⁶ and C⁶ will operate to restore the condition existing at the time of the sounding of the note by perforation N¹³ so that when the chord indicated by perforations N¹⁵, N¹⁶, N¹⁷, and N¹⁸, in which the last named perforation controlled the theme note, may be sounded in similar manner, that is to emphasize or accentuate the theme note. In this instance the theme note N¹⁸ is moved forward sufficiently to be beyond the influence of the intensity reducing perforation A⁶. Thus the three accompaniment notes of the chord are subdued without affecting the theme note.

Thus in all cases requiring a displacement of note perforations from their natural relations, those for the louder notes are advanced beyond the others, and the latter are placed properly in relation to the intensity reducing perforations to reduce the intensity of notes played thereby.

The illustrative note sheet shows another expression controlling perforation D⁶ which further reduces playing intensities prior to the sounding of a note by perforation N¹⁹,

while the expression controlling perforations B³, C⁶ and F⁵ operate to increase playing intensities before the sounding of a note by perforation N²⁰.

- 5 The advantages of the present arrangement whereby a selected note is accented will be apparent at once to those skilled in the art. In order to preserve the unity of a chord it is essential that the theme or accented note be not advanced or retarded to such an extent that the ear may easily detect the fact that it is not struck precisely simultaneously with the other notes in the chord. Therefore the interval for readjusting the degree of exhaust in the action wind chest is of necessity very small and the smaller it can be made the better will be the resultant musical effect. The degree of exhaust in an action wind chest may be adjusted to a lower level more quickly and surely than it can be to a higher level. Furthermore, the act of striking one or more notes tends to reduce, momentarily, the degree of exhaust.
- 25 The present arrangement enables the degree of exhaust to be adjusted to the proper intensity for the theme or accented note a substantial interval of time before the same is struck and immediately thereafter the degree of exhaust is reduced so that the accompaniment notes are struck with subdued intensity. The very act of striking the theme note reduces somewhat the degree of exhaust in the action wind chest and contributes to the reduction of the intensity of the accompaniment notes which are struck somewhat later.

It is to be understood that the invention herein described is not limited to the preferred embodiment thereof selected for illustrative purposes but may be modified and variously embodied within the scope of the subjoined claims.

I claim as my invention:

1. A perforated sheet for tone-governing apparatus, comprising a plurality of perforations for tones to be played in a group substantially simultaneously, a perforation for a relatively loud tone being advanced beyond a perforation for a relatively soft tone; and an intensity-reducing perforation retreated rearwardly of the louder-tone perforation, to cooperate with the softer-tone perforation.
2. A perforated sheet for tone-governing apparatus, comprising a plurality of perforations for tones to be played in a group substantially simultaneously; and an intensity-reducing perforation substantially aligned with one said tone perforation and to the rear of another such tone perforation.
3. A perforated sheet for tone-controlling apparatus, comprising a plurality of perforations for tones to be played in a group substantially simultaneously; intensity-increasing perforations to cooperate with some of them; and intensity-reducing perforations substantially aligned with other tone perforations with which they operate.

In testimony whereof, I have signed my name to this specification this 11th day of March, 1922.

CHARLES F. STODDARD.
